UNITED STATES PATENT OFFICE

GUSTAF SAMUEL OLSON, OF NEW YORK, N. Y.

REAMER

Application filed December 20, 1928. Serial No. 327,210.

The invention relates to reamers and has for its object to provide a simple and efficient reaming device capable of being easily and quickly attached to and detached from die stocks of conventional form. A further object of the invention is to provide a construction in which the reaming tool is adjustable for different sizes of reaming, and in which said reamer automatically assumes an inoperative position when the bore upon which it is operating is properly reamed out. The invention contemplates further a reamer in which the working pressure on the reaming tool is capable of being readily adjusted for different kinds of material, and for different depths of reaming. Other objects will appear from the description hereinafter and the features of novelty will be pointed out in the claims.

In the accompanying drawing, which illustrates an example of the invention without defining its limits, Fig. 1 is a sectional elevation of the reamer attached to a die stock; Figs. 2 and 3 are side elevations of the reamer itself, showing the parts in different positions; Fig. 4 is a section on the line 4—4 of Fig. 1; Fig. 5 is an inverted plan view of the reamer; Fig. 6 is a plan view thereof; Fig. 7 is a section on the line 7—7 of Fig. 1, and Fig. 8 is a view of a combined adjusting and indicating member.

The reamer comprises an outer hollow casing 10, preferably of cylindrical form, and provided at one end with outwardly projecting lugs 11 whereby the reamer is adapted for detachable connection with a conventional die stock in a manner to be more fully set forth hereinafter. A cylindrical sleeve 12 is mounted in the casing and slidably fits an internal annular shoulder 13 with which the casing is provided, said sleeve itself being provided with an annular flange 14 slidably fitting the casing 10, as shown in Fig. 1. The sleeve 12 is screw-threaded at its upper end for the accommodation of a collar 15, which bears against the end face of the casing 10 and limits the sliding movements of the sleeve 12 in one axial direction relatively to the casing 10. A spring 16 surrounds the sleeve 12 within the casing 10

and bears with its one end against the shoulder 13 of said casing and with its other end against the annular flange 14 of the sleeve; if desired, suitable washers 17 may be interposed between the ends of the spring 16 and the shoulder 13 and flange 14, respectively. The reamer further comprises a tubular member 18 extending axially of the sleeve 12 and slidably guided therein by an annular shoulder 19 with which the sleeve 12 is provided, said tubular member 18 at its lower end being continued in the form of a hollow head 20 shaped and dimensioned to slidably fit within the sleeve 12, as shown in Fig. 1. A socket member 21 extends axially of the hollow head 20 and projects into the tubular member 18, said socket member 21 being dimensioned and shaped to slidably fit the interior of the tubular member 18; at its lower end the socket member 21 is formed with an annular flange 22, which slidably fits within the head 20, said socket member being further provided with an axial bore adapted to receive the stem 23 of the reaming tool 24. Any suitable means may be provided for removably connecting the reaming tool 24 with the socket member 21, the illustrated example showing the latter provided with a set screw 25 whereby this is accomplished. The outer casing 10, the sleeve 12, the tubular member 18, the head 20 and the socket member 21, together with their associated elements may be termed a "carrier" on which the reaming tool 24 is mounted and whereby said tool may either be manipulated or connected with a die stock for manipulation thereby. In order to prevent the reaming tool 24 from rotating about its axis relatively to the head 20, any suitable means may be provided as, for instance, by making the interior of the head 20 and the flange 22 of corresponding hexagonal form. For the purpose of adjusting the position of the reaming tool on the carrier, the socket member 21 is continued in the form of a screw threaded stem 26 projecting upwardly in the tubular member 18 into screwthreaded engagement with an internally threaded cylindrical nut 27; the latter is rotatably mounted in the tubular member 18 and is

provided with an external annular flange 28, which bears against the upper end of said tubular member 18 and thereby prevents inward movement of the nut 27 into the same without interfering with the relative rotation of said nut. A cylindrical boss 29 projects from the end of the nut 27 in an axial direction through an axial opening in a cap 30 which is threaded upon the tubular member 18 into engagement with a ring 31, also threaded upon said member 18 and lying in surface engagement with the end of the sleeve 12 and projecting over the annular collar 15, as shown in Fig. 1. This cap 30 prevents movement of the nut 27 in an outward direction relatively to the member 18 without, however, interfering with the aforesaid rotation of said nut in said member. For the purpose of facilitating the manipulation of the nut 27, the boss 29 is provided with openings 32 extending diametrically through the same for the accommodation of a suitable tool 33, such as shown, for instance, in Fig. 8; the boss 29 is further provided with a channel 34 extending axially through the same into communication with the interior of the nut 27, said channel permitting the tool 33 to be inserted lengthwise of the nut 27 into engagement with the end of the stem 36. By providing the tool with suitable markings 35, designating the various positions of the reaming tool 24, the extent to which said tool projects beyond the head 20 which constitutes its operative position may be readily ascertained by simply inserting the tool 33 through the channel into engagement with the end of the stem 26 and then noting the designation 35 thereof which is nearest to or registers with the end surface of the boss 29. A coil spring 36 surrounds the tubular member 18 within the sleeve 12 and with its one end engages the head 20, and with its other end contacts with an annular washer 37; the tension of the spring 36 may be varied for the purpose to be more fully described hereinafter by means of adjusting screws 38 in threaded engagement with the annular flange 19 and passing through suitable openings 39 formed in the ring 31. The sleeve 12, tubular member 18, head 20, socket member 21 and associated elements which, together, may be termed a "core", are capable of rotating as a unit within the casing 10. In order to permit said rotation in one direction and to prevent it in the opposite direction, a ratchet means is provided which, in the illustrated example, comprises studs 40 projecting outwardly from the end surface of the casing 10 in perpendicular relation thereto, said studs 40 being carried by heads 41 slidably mounted in recesses 42 formed in the casing 10 and being controlled by means of coil springs 43 tending to force said studs outwardly. The studs 40 extend into recesses 44 formed in the collar 15, said recesses each having one end shouldered to

prevent the collar 15 from rotatably moving beyond the studs 40 and being beveled at their other ends to permit relative rotation of said collar 15 in the other direction. With this arrangement, it is possible to rotate the casing 10 about and relatively to the axis of the reaming tool 24 and thus prevents the latter from being moved in a backward direction relatively to the work and thereby prevents injury to the cutting edges of said tool. In order to prevent the cuttings resulting from the reaming operation from passing into the interior of the casing 10, a felt or other washer 45 is fitted upon the sleeve 12 against the flange 14 thereof and is held in place in any suitable manner as by means of a locking ring 46. The reamer further includes locking means whereby the reamer 34 is held in its operative position on the carrier, which locking means is releasable by pressure developed by the work to permit the reaming tool to be automatically shifted to an inoperative position when a predetermined point in the reaming operation is reached. In the illustrated example this locking means comprises locking levers 47 extending lengthwise of the casing 10, preferably at diametrically opposite external points thereof, said levers being pivoted at 48 to said casing and being urged inwardly by means of leaf springs or their equivalent 49, which are secured to the casing in any convenient manner, as by screws 50. The upper ends of the locking levers 47 are provided with sharply defined locking shoulders 51 adapted to project over the collar 15 and with inclined camming shoulders 52 arranged to engage a correspondingly beveled surface 53 with which the ring 31 is provided, as shown in Figs. 2 and 3.

The reaming device is illustrated in a form adapting it to be easily and quickly connected with a die stock of conventional form, it being understood, however, that the novel features may be embodied in a reamer which is operated otherwise than by means of such die stock. To enable the reamer to be detachably combined with the die stock, the lugs 11 are provided with suitable apertures 54 for the accommodation of bolts 55, which correspond to the bolts usually found in customary die stocks, excepting that they may be made somewhat longer in order to permit the reamer to be connected with the die stock without interfering with the presence of the usual thread cutting die 56 therein. The latter is additionally held in place in the well known way by means of the usual set screws 57 which are in screwthreaded engagement with lugs 58 with which the die stock 59 is provided. The latter includes the usual guide 60 for the work 61 and the conventional handles 62 whereby the die stock is manipulated.

In practice and assuming that the reamer

has been connected with the die stock, as shown in Fig. 1 of the drawings, the reamer is adjusted to the desired operative position on the carrier by suitably manipulating the 5 nut 27 to screw the stem 26 into or out of said nut and to thereby adjust the socket member 21 lengthwise of the cap 20 and to correspondingly move the reaming tool 24. After this setting has been accomplished, the work 61, 10 which, as shown, may be a pipe, is clamped in a vise in the usual manner and then the die stock guide 60 is inserted over the end thereof to cause the reaming tool to project into said pipe in the usual manner. A manipulation of the die stock in the well known 15 way will thus cause the reaming tool 24 to be rotated about its axis and relatively to the pipe 61 and accordingly will ream out said pipe in the conventional way. As the reaming 20 operation proceeds the pressure exerted by the reaming tool 24 against the pipe 61 and the counter pressure developed by the latter will gradually force the reaming tool 24 in a backward direction and cause the head 25 21, tubular member 18, and bevelled ring 31 to correspondingly move in the same direction against the tension of the spring 36. As these operations take place the bevel 53 of the 30 ring 31 in co-operation with the camming shoulders 52 will gradually force the locking levers 47 outwardly against the tension of 35 the springs 49. As this outward movement of the levers 47 continues, the locking shoulders 51 will finally be forced out of engagement with the collar 15 and will thus permit 40 the sleeve 12 to be also moved in an axial direction relatively to the casing 10 to thereby automatically disconnect the studs 40 from the recesses 44 and thus bring the reaming 45 tool 24 to an inoperative position on the carrier. This takes place at the instant when the reaming operation has been completed in a predetermined manner. If, coincidentally with the reaming of the pipe 61 a thread is being 50 cut thereon, this threading operation may be completed without interference from the reaming tool 24. In any case, when the die stock is removed from the pipe 61 the spring 16, which has been compressed during 55 the shifting of the reaming tool 24 to its inoperative position, will immediately restore the reaming tool, through the medium of its associated elements, to the normal operative position to which it previously had been set. In 60 order to clearly define what is meant by the inoperative position of the reaming tool, it may be said that the aforesaid axial movements of the parts relatively to the casing 10 disconnect the studs 40 from the ratchet recesses 40, so that the casing 10 is free to rotate relatively to the reaming tool 24 which, together with its associated elements, is held 65 against rotation by its engagement with the pipe 61, so that the aforesaid threading op-

eration may be continued to completion without interference.

The working pressure on the reaming tool 24 may be adjusted to adequately meet the requirements of different kinds of material 70 and for different depths of reaming, by simply adjusting the set screws 38 and thereby either bringing about a compression or expansion of the spring 36. In this way the resistance to the aforesaid backward movement of the reaming tool is either increased or diminished and the backward travel accordingly retarded or hastened. If removal or replacement of the reaming tool 24 is desired, it is simply necessary to rotate the 75 nut 27 to an extent sufficient to disconnect the stem 26 therefrom and to thus permit the socket member 21 and with it the reaming tool 24 to be withdrawn from the carrier after which the reaming tool 24 may be 80 easily removed by simply loosening up on the set screw 25. The reaming attachment may be constructed and dimensioned to fit any type of die stock and in all cases is capable of being easily and quickly combined 85 therewith and detached therefrom. With the reamer shown and described, the operations of reaming out a pipe and threading the same externally may be coincidentally carried on without interference, one with the 90 other.

Various changes in the specific forms shown and described may be made within the scope of the claims without departing from the spirit of the invention.

I claim:

1. A reamer comprising an outer casing, a core rotatably mounted in said casing, a reaming tool mounted on said core to rotate therewith about its axis, and adjustable 105 in the direction of said axis relatively to said core and casing, ratchet mechanism for fixing said core and tool against rotation relatively to the casing in one direction, and for permitting said casing to relatively rotate about said axis in the opposite direction to thereby prevent backward rotation of the reaming tool relatively to the work, and means permitting the reaming tool to be automatically shifted in an axial direction by 110 pressure upon the work whereby said ratchet mechanism is disconnected and said reaming tool is adjusted to an inoperative position on said casing at a predetermined point in the reaming operation.

2. A reamer comprising an outer casing, a core rotatably mounted in said casing, a reaming tool mounted on said core to rotate therewith about its axis, and adjustable in the direction of said axis relatively to said core and casing, ratchet mechanism for fixing said core and tool against rotation relatively to the casing in one direction, and for permitting said casing to relatively rotate about said axis in the opposite direction to 115 120 125 130

thereby prevent backward rotation of the reaming tool relatively to the work, means permitting the reaming tool to be automatically shifted in an axial direction by pressure upon the work whereby said ratchet mechanism is disconnected and said reaming tool is adjusted to an inoperative position on said casing at a predetermined point in the reaming operation, and adjustable means for varying the working pressure on said tool.

3. A reamer comprising an outer casing adapted for detachable connection with a die stock, a sleeve slidably mounted in said casing, a spring surrounding said sleeve within said casing and arranged to maintain and return said sleeve in and to its normal position, a hollow head slidably fitted in said sleeve, a tubular member comprising an axial continuation of said head, a spring within said sleeve bearing against said head, means for varying the tension of said last named spring, a socket member slidable in said hollow member, a reaming tool secured in said socket member, a threaded stem comprising an extension of said socket member, a sleeve nut rotatably mounted in said tubular member and in threaded engagement with said threaded stem whereby the operative position of said reaming tool on said reamer may be varied, locking levers whereby said reaming tool is secured in its operative position on said casing, and means actuated by pressure developed by the work for releasing said locking levers to automatically adjust said reamer to an inoperative position on said casing.

In testimony whereof I hereunto set my hand.

GUSTAF SAMUEL OLSON.
